ATTORNEY.

UNITED STATES PATENT OFFICE.

MATHIAS BRAUN, OF PHILADELPHIA, PENNSYLVANIA.

LAWN-MOWER.

SPECIFICATION forming part of Letters Patent No. 252,352, dated January 17, 1882.

Application filed June 24, 1881. (No model.)

To all whom it may concern:

Be it known that I, MATHIAS BRAUN, a citizen of the United States, residing in the city and county of Philadelphia, State of Pennsylvania, have invented a new and useful Improvement 5 in Lawn-Mowers, which improvement is fully set forth in the following specification and accompanying drawings, in which—

Figure 1 is a side elevation of the inner face 10 of the portion of the lawn-mower embodying my invention. Fig. 2 is a section in line $x-x'$, Fig. 1. Fig. 3 is a section in line $y-y'$, Fig. 4. Fig. 4 is a vertical section in line $z-z'$, Fig. 5. Fig. 5 is a horizontal section in line $z'-z'$, Fig. 4. Fig. 6 is a top or plan view of the portion of the 15 lawn-mower embodying my invention. Fig. 7 is a perspective view of one of the pawls thereof.

Similar letters of reference indicate corresponding parts in the several figures.

My invention consists of novel means for securely binding or connecting the frame of the mower.

It also consists of novel means for securely 25 and adjustably attaching the braces of the handle to the frame of the mower.

Referring to the drawings, A A represent the wheels of the mower, and B the shafts or axles thereof, which are cast with or connected 30 to the plates C of the frame of the mower.

D represents a ratchet rim or wheel, which is cast with or secured to the wheel A on the inner side thereof, and adapted to be engaged by the pawls E E on the hub F of the gear-wheel F', which latter is freely mounted on the shaft B, and communicates motion by means of an idler to a wheel secured to the rotary cutter of the mower, the bearings of the shaft of said cutter being shown at G, Figs. 1, 4, and 6.

40 Projecting horizontally inwardly from the plates C C are lugs H, cast therewith, and surrounding the lugs are brackets J, which, secured to the plates, have openings of larger diameter than said lugs, the walls of said openings being threaded for engagement with the threaded end of a tubular, or partly tubular, shaft, rod, or bar, K, the threads of the ends of said shaft being in reverse order, or right and left.

50 It will be seen that when the tubular ends of the shaft are screwed into the brackets J said ends encircle the lugs H, and are thus

braced without by the brackets and within by the lugs, and vastly strengthened. The rod or shaft serves to bind the plates C of the frame, 55 and as this is assisted by the shaft of the rotary cutter, the bed-knife, and other parts of the mower, it is evident that the frame is surely connected, and is consequently firm, strong, and durable. 60

L represents the braces of the handle M, each of which has at its inner end a segmental slot, N, and adjacent thereto a cylindrical opening, P. Projecting from the plates C at the places of connection of the braces L are segmental 65 lugs Q and cylindrical lugs R. The lugs Q enter the segmental slots N and the lugs R enter the cylindrical openings P.

It will be seen that the lugs R act as fulcra for the braces L, so that the angle of the handle 70 to the mower may be readily adjusted. When the adjustment of the handle is accomplished screws S are passed through openings in the lugs Q and forced against washers T, interposed between the heads of the screws and 75 outer ends of the lugs, the washers being of such dimensions that they overlap the edges of the slots N and tighten against the braces L, whereby the latter are securely held.

The special construction of the pawl-and-ratchet mechanism is the subject for a separate application for Letters Patent, and is not claimed in the present case.

Having thus described my invention, what I claim as new, and desire to secure by Letters 85 Patent, is—

1. In a lawn-mower, a binding rod or shaft, with tubular externally right and left hand screw-threaded ends, in combination with an annular internally right and left hand screw-threaded hollow brackets which receive said ends and lugs which enter said ends, said lugs and brackets being fast to the frame of the mower, substantially as set forth.

2. The side plates, C, each having cast with it the cylindrical lug R and segmental lug Q, the handle-braces each provided with the circular opening P and segmental slot N, the screw S, and the washer T, all combined and operating substantially as set forth.

MATHIAS BRAUN.
